UNITED STATES PATENT OFFICE.

MILO S. WALKER, OF CHICAGO, ILLINOIS, ASSIGNOR OF TWO-THIRDS
TO MAX HERSKOVITZ AND ABRAHAM L. HERSKOVITZ, OF CHICAGO,
ILLINOIS.

BURNER.

SPECIFICATION forming part of Letters Patent No. 707,286, dated August 19, 1902.

Application filed October 7, 1901. Serial No. 77,829. (No model.)

To all whom it may concern:

Be it known that I, MILO S. WALKER, a citizen of the United States of America, residing at Chicago, in the county of Cook and State of Illinois, have invented certain new and useful Improvements in Burners, of which the following is a specification.

My invention relates to improvements in burners of the so-called "Bunsen" or "color-less-flame" type, the object of which is to effect a more perfect combination of air and gas for the purpose of increasing the heating capacity whereby under a given gas-pressure a larger mantle can be heated to complete incandescence than with the use of the ordinary Bunsen burner.

In general my improvement consists in an apparatus whereby gas from a suitable supply is delivered under pressure through a small orifice or nozzle, thereby forming a swiftly-moving jet, said jet drawing with it a certain quantity of air, the mixture thus formed passing through an elongated passage on its way to the point of combustion of the burner. This mixture of gas and air, however, before entering the passage-way referred to passes by a series of hooded openings, where it receives a further supply of air, thereby furnishing said jet with a perfect mixture of gas and air before reaching the point of combustion. The apparatus by which this arrangement is attained is shown in a drawing accompanying this specification by means of a central longitudinal section of a burner constructed on the plan of the preferred form and arrangement.

In the drawing, A represents a tubular casting, the bottom of which is closed by a perforated plug a, in which is threaded a nozzle B, having upon its lower end an internally-screw-threaded nipple b for attachment to a gas-fixture. The upper end of the nozzle contains a small orifice b', through which the gas is forced in a small and swiftly-moving jet. Above the plug a and preferably below the end of the nozzle are openings a' in the tube A for the admission of air into the mixing-chamber A' of the burner. The size of the openings a' may be regulated by a sleeve C, having openings c, adapted to register

with the openings a' in the tube or to be moved thereupon to reduce the size thereof, so as to regulate the quantity of air drawn in at this point.

Above the nozzle B is a second set of openings a² in the tube A, which openings are shielded by a hood a³ to prevent a current of air from passing directly across the mixing-chamber, and thereby interfering with the perfect operation of the burner. Said hood does not, however, prevent the free access of air to the mixing-chamber at this point, as the annular space between it and the tube is quite sufficient to allow the required quantity of air to enter.

Above the hooded perforations a² is secured a diaphragm D, having an aperture in line with the nozzle, and in said aperture is secured a tube E, extending up beyond the diaphragm for quite a distance to form an elongated passage-way through which the thoroughly-mixed gas and air must pass to the point of combustion. It will thus be understood that when gas is delivered to this burner, it must pass through the nozzle, and up therefrom in the form of a jet moving at considerable speed, that the jet thus formed will draw in air through the openings a' and deliver it, together with the gas, through the tube E into the chamber A². That this jet of gas and air mixture, acting upon the principle of an injector will draw in with it a further supply of air through the openings a² before entering the tube E, and thereby receive a sufficient quantity of air which becomes thoroughly mixed with the gas, and when delivered to the chamber A² produces a flame of intense heat, which when applied to a mantle heats the same to perfect incandescence.

In this manner a larger mantle can be used in connection with the burner, which because of the perfect combustion attained, and consequently the intense heat produced, enables the same to heat a large mantle to perfect incandescence. In burners of the ordinary kind, although using more gas, they are unable to get a perfect mixture of gas and air, and consequently the required amount of heat.

A series of openings a² above the top of the nozzle furnish a constant supply of air, pro-

tected as they are by the hood a^3 , and at the same time the additional or supplemental openings a' furnish a means of nice adjustment, through which complete combustion 5 may be attained and any variation in the pressure of gas compensated for. The combination of the two sets of openings gives greater delicacy of adjustment, inasmuch as the lower and adjustable set may be used entirely for the purpose of varying the supply 10 of air, while the upper set furnish the minimum supply and are never interfered with by the adjustment of the lower set. To attain the result produced by this burner, both 15 sets of openings should be in the mixing-chamber, in which the gas mingles with the air prior to its passage through the tube E into the chamber A^2 , and it is greatly preferable that the constant openings be above 20 the end of the nozzle and be hooded or otherwise shielded and the adjustable openings be below the top of the nozzle and be provided with means for varying their size to suit the requirements.

25 I claim as new and desire to secure by Letters Patent—

1. In a gas-burner, the combination with suitable walls inclosing a mixing-chamber, of a gas-nozzle entering said chamber, the lateral walls of said chamber being independently perforated above and below the end of said nozzle and the top wall thereof being perforated in line with said nozzle, and a suitable extension inclosing a chamber beyond 30 the perforation in said top wall; substantially as described.

2. In a gas-burner, the combination with

an inlet-nozzle, of an inclosed mixing-chamber which said nozzle enters, provided with a lower series of openings below the end of the 40 nozzle and having means for adjustment and an upper series of openings above the end of the nozzle, a hood arranged about the upper series of openings, a chamber above the mixing-chamber and a diaphragm between the 45 two having a connecting-opening in line with the nozzle; substantially as described.

3. In a gas-burner, the combination with a tubular chamber having two sets of perforations, the upper set of which is inclosed by 50 a suitable hood, of a nozzle opening between said two sets of perforations, a diaphragm in said chamber above the perforations and a reduced tube secured in said diaphragm and in alinement with the nozzle; substantially 55 as described.

4. In a gas-burner, the combination with the tubular casing, A, having perforations, a' , a^2 , at different points in its length, of a nozzle, b, opening between said perforations, 60 a hood, a^3 , inclosing the uppermost of said perforations, a diaphragm, D, extending across the tubular casing, A, and a tubular passage, E, connected to said diaphragm; substantially as described. 65

In witness whereof I have hereunto set my hand, at Chicago, in the county of Cook and State of Illinois, this 1st day of October, A. D. 1901.

MILO S. WALKER.
